UNITED STATES PATENT OFFICE.

JOHN G. ZOLLMAN, OF CHICAGO, ILLINOIS.

CALCULATING DEVICE.

Application filed July 23, 1923. Serial No. 653,329.

To all whom it may concern:

Be it known that I, JOHN G. ZOLLMAN, a citizen of the United States, and a resident of Chicago, in the county of Cook and State of Illinois, have invented a new and useful Improvement in Calculating Devices, of which the following is a full, clear, and exact description.

My invention relates to improvements in calculating devices, and it consists in the combinations, constructions, and arrangements herein described and claimed.

An object of my invention is to provide a calculating device which is extremely simple in construction, that is capable of performing a multiplicity of mathematical problems and in a relatively short time.

A further object of my invention is to provide a device of the character described in which the dials upon which the scales are imprinted are removable so that new dials having scales of different values may be substituted therefor.

A further object of my invention is to provide a device of the character described in which a novel means is employed for mechanically establishing a rotative connection between two cooperating dials.

Other objects and advantages will appear in the following specification, and the novel features of the invention will be particularly pointed out in the appended claims.

My invention is illustrated in the accompanying drawings, forming part of this application, in which—

Figure 1 is a top plan view of an embodiment of my invention.

Figure 2 is a side elevation of the mechanism illustrated in Figure 1, partly in section,

Figure 3 is a view along the line 3—3 of Figure 2, and

Figure 4 is a sectional view along the line 4—4 of Figure 1.

In carrying out my invention, I make use of a substantially flat rigid base 1. The base 1 is provided with an upright pin 2 rigidly secured thereto and a tubular sleeve 3 likewise extending upwardly from the base 1 and at a spaced distance from the pin 2.

A pair of rigid fiber scroll gears 4 and 5 are rotatably mounted upon the pin 2 and the sleeve 3 respectively. These gears are in mesh with one another.

A dial 6, which I choose to call the number dial, is fixed to the gear 4 in the manner

shown in Figure 2 and is concentric with the pin 2. This number dial is provided with legends on its upper face arranged in concentric rings encompassing the entire circumference of the dial. The first ring is calibrated in numbers from 10 to 100, as indicated at 7. The second and third rings 8 and 9 are calibrated in values corresponding to the square of predetermined values. The calibrations in the first ring are for the square having values from 10 to 32 and the calibrations in the second ring are for squares having values from 32 to 100. The next three rings 10, 11, and 12, respectively, are calibrated in values relating to cubes, the first ring being for numbers from 10 to 22, the second ring being for numbers from 22 to 47 and the third ring for numbers from 47 to 100. The next two rings on the inner side of the rings 10, 11, and 12, as indicated at 13 and 14, are for sign values, these rings being indicated at 7 and 8 on the indicating plate 15. The first ring 13 is for sign values from zero degrees to 6 degrees, while the second ring 14 is calibrated in values from 6 degrees to 90 degrees. The last three rings 16, 17 and 18 are calibrated in values relating to tangents, the first ring being calibrated from 6 degrees to 45 degrees, the second calibrated from 45 degrees to 84 degrees, and the third ring calibrated from 84 degrees to 90 degrees. There are therefore eleven concentric rings on the dials 6, each calibrated in certain values and the character of the calibrations are indicated clearly on the index card 15. This card is supported on a supporting member 19 at one end and has an opening 20 therethrough, through which the pin 2 is projected and the opposite end of the card permitted to project beyond the pin 2 as indicated at 21.

A transparent strip 22, preferably of celluloid or the like, is also secured to the supporting member 19 at one end and likewise is provided with an opening therethrough for permitting the admittance of the pin 2. This transparent strip has a hair line 23 imprinted or cut thereon which passes directly through the center of the pin 2. This hair line is used for reading values of the legends in the rings 1 to 11 inclusive.

A second dial 24, similar in size to the dial 6, is provided with an upwardly extending annular sleeve 25 at its central point, which sleeve has a plurality of slots, one of which is indicated at 26 in Figure 4, adjacent its

lower end and extending longitudinally of the sleeve. The sleeve is permitted to exactly overlie the upwardly extending tubular sleeve 27 secured to the gear 5 for a portion of its length, as indicated in Figure 4 so that the dial 24 may be rotated upon the tubular member 27 and relative to the scroll gear 5. Means for securely fixing the dial 24 against movement relative to the scroll gear 5 is provided in a resilient ring 28 disposed about the sleeve 25 and arranged to be manually moved longitudinally of that sleeve. When the ring 28 is in the position shown in full lines in Figure 4, the scroll gear 5 may be turned freely relative to the stationary dial 24, but when the resilient ring 28 is disposed in the position shown in dotted lines, then the dial 24 must turn with the scroll gear 5.

20 The dial 24 is provided with three rings 29, 30, and 31 imprinted adjacent the peripheral edge 33 thereof, one within the other in the same manner as the legend rings of the dial 6. The first ring 29 has legends thereon representing the log values of the numbers on the number ring 7 on the dial 6, that is, numbers from 1 to 10 and from 10 to 100 and the like. The legends in the ring 30 are calibrated to represent 25 the multiplicand of numbers on the number ring 7 of the dial 6, while the legends on the ring 31 are merely an inverted replica of the numbers on the dial 30 and are used for the process of division.

30 The scroll gears are of such relatively varying radii that any given angular rotating movement of one gear about its center will cause an angular rotating movement of the other gear proportional to the log 35 value of the number indicated on the first dial.

From the foregoing description of the various parts of the device, the operation thereof may be readily understood. Let us assume that it is desired to find the log 40 value of any of the particular numbers on the ring 7 of the dial 6. If this number is let us say 100 or 10, as shown in Figure 1, the dial is moved until 100 is directly under the hair line 23. The log value of 45 1 is zero, as indicated on the dial 24 by the legends 29.

Let us assume that it is desired to solve 50 a problem in multiplication as for common fractions and proportions. In this event it is necessary to place the denominator on the number dial on the scale 1 (see index 55 15) directly under the hair line 23. The resilient ring 28 is moved to the position 60 shown in full lines in Figure 4 and the dial 24 is manually rotated relative to the scroll gear 5 until the third term of the problem is on the black log scale, i. e., the dial 30.

65 The resilient ring 25 is then moved to the

position shown in dotted lines in Figure 4 so that the dial 24 will move with the gear and the upper dial 6 is rotated so that the numerator at this time on the scale 7 falls under the hair line 23. The fourth term 70 of the problem will appear directly under the hair line 23 upon the dial 24 of the black log scale. The word "black" is used to distinguish the scale 30 from the scale 31. The inverted scale which is in the ring 75 31 is printed in red ink and referred to as the red log scale. The legends on the ring 29 are merely log values and not results calculated on the scales 30 and 31. To solve a problem in division, it is necessary 80 to turn the number dial until the divisor readable on the scale 7 is directly under the hair line 23. The dividend, readable upon the black log scale or the scale 85 30, is then placed under the hair line 23 and the number dial is then rotated (at this time the ring 28 must be in the position shown in dotted lines in Figure 4) so that 10 appears under the line 23 on the scale 7. The quotient is readable directly 90 under the hair line 23 on the scale 30.

To solve problems in squares and cubes and the reverse, their roots, the scales 2 to 6 are employed. Let us assume that it is 95 desired to figure the area of a surface of a sphere having a radius of 67 inches. The number dial is set on the scale 1 so that 10 is under the hair line 23. The dial 24 is then moved so that the reading 4 pi on the scale 30 is under the hair line. The number dial is then moved (with the resilient ring 28 in the position shown in dotted lines) until 67 appears on scale No. 3 directly under the line 23. The answer, that is the area of the surface of the sphere, is 100 read on the black log scale 30 directly under the hair line.

Problems requiring sines or tangents are read after the following fashion. Let us say that it is desired to find the area of a 110 triangle, two of the sides being given as follows. A equals 26, B equals 43, and sine C equals 47 degrees and 35'. It is known that multiplying by a number is equivalent to dividing by its reciprocal. We may take 115 3.846, the reciprocal of 26, (calculate it by use of the scale 31) and place this number on the scale 1 of the dial 6 under the hair line 23. We then move the dial 24 so that 43 appears under the hair line 23 120 on the scale 30. The number dial is then turned until 38 degrees and 41' is under the line 23 (see scale 8). The answer is found to be 836.5 on scale 31.

I claim:

1. A calculating device of the character described comprising a pair of rotatably mounted dials having legends thereon representing mathematical values and calculation, a pair of scroll gears, one for each of 130

said dials, arranged to turn with said dials, said scroll gears being in mesh with one another, the ratio of said gears relative to one another being such as to cause the 5 rotation of one dial when the opposite dial is turned, said scroll gears having such relatively varying radii that any given angular rotating movement of one gear about its center and the consequent movement of its dial will cause an angular rotating movement of the other gear proportional to the log value of a predetermined number indicated on the first named dial.

2. A calculating device of the character

described comprising a pair of rotatably mounted disks having legends thereon representing mathematical values and calculations, a scroll gear associated with one of said dials, a second scroll gear associated with the remaining dial, and in mesh with the first named gear, said scroll gears being constructed as to their varying radii so as to increase the radii in a logarithmic ratio about the working center of the gears, and manually operated means for engaging 25 and disengaging said scroll gear with its associate dial.

JOHN G. ZOLLMAN.
